(Cl. D34—15)

To all whom it may concern:

Be it known that I, Albert Dickson, a citizen of the United States, residing at Pontiac, county of Oakland, in the State of Michigan, have invented a new, original, and ornamental Design for a Toy Amphibian Truck or Similar Article, of which the following is a specification, reference being made to the accompanying drawing, forming part thereof.

Fig. 1 is a side elevational view of a toy amphibian truck or similar article embodying my new design.

Fig. 2 is a plan view thereof.

Fig. 3 is a front view thereof.

Fig. 4 is a rear view thereof.

I claim:

The ornamental design for a toy amphibian truck or similar article, as shown.

ALBERT DICKSON.
